Primary Examiner—Austin Murphy(74) *Attorney, Agent, or Firm*—Holland & Hart, LLP(57) **CLAIM**

The ornamental design for microphone shock absorber, as shown and described.

DESCRIPTION

FIG. 1 is a perspective view of microphone shock absorber showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view in use; the portions shown in dashed lines do not form part of the design.
